Fig. 2

Fig. 11

Des. 175,907

PAGE 3

Fig. 1 is a side elevational view of a trailer body showing my new design.

Fig. 2 is a side perspective view thereof shown in reduced scale.

Fig. 3 is a side elevational view opposite that shown in Fig. 2.

Fig. 4 is a front elevational view of said body.

Fig. 5 is a rear elevational view of said body.

Fig. 6 is a top plan view on a slightly reduced scale.

Fig. 7 is a side elevational view with the roof extensions and supports therefor and the counter elements in folded position.

Fig. 8 is a side elevational view similar to that shown in Fig. 3 with the roof extensions and supports therefor in folded position.

Fig. 9 is a rear elevational view similar to Fig. 4 except that the roof extensions, supports therefor, and counter element are in folded position.

Fig. 10 is a rear elevational view similar to Fig. 5 except that the roof extensions, supports therefor, and counter are in folded position.

Fig. 11 is a top plan view with roof extensions, supports therefor, and counter in folded position.

The wheels, hitch, and mast shown by means of broken lines are disclosed only for the purpose of illustration.

I claim:

The ornamental design for a trailer body, as shown and described.
